UNITED STATES PATENT OFFICE.

WILLIAM H. NICKERSON, OF BROOKLINE, MASSACHUSETTS.

SHANK-STIFFENER MACHINE.

Application filed July 9, 1925. Serial No. 42,455.

This invention relates to mechanism for forming shoe shank stiffeners from strips of indeterminate length, the stiffeners having integral prongs at their opposite ends.

The invention is embodied in the improved forming and pronging means hereinafter described.

Of the accompanying drawings forming a part of this specification,—

10 Figure 1 shows in vertical section the elements in which my invention is embodied, said elements including forming dies acting on a portion of a strip to impart thereto a curved and ribbed form, and punching dies adapted to sever each formed portion from the strip and at the same time form prongs on the severed portion and on the strip.

Figure 2 is a top plan view showing the lower forming die and the lower punch die.

20 Figure 3 is a bottom plan view showing the upper forming die and the upper punch die.

Figure 4 is a section on line 4—4 of Figure 1.

25 Figure 5 is a section on line 5—5 of Figure 1.

Figure 6 is a section on line 6—6 of Figure 5, showing the members of the upper punch die in section, and an end view of the 30 lower punch die, the strip being shown by dotted lines.

Figure 7 is an isometric view showing the punch dies separated and portions of the strip after it has been severed and provided 35 with prongs.

Figure 8 is a fragmentary perspective sectional view showing a portion of the upper punch die.

40 Figures 9 and 10 are fragmentary perspective views illustrating the operation of severing and pronging the strip.

Figure 11 shows in perspective a blank removed from the strip during the punching and pronging operation.

45 Figure 12 is a perspective view showing a completed stiffener.

The same reference characters indicate the same parts in all of the figures.

12 designates a base fixed to a press bed 13.

50 Fixed by screws 14 to the base is a lower forming die 15 having a curved longitudinal

embossing rib 16, and curved forming faces 17 at opposite sides of the rib.

18 designates an upper forming die having a curved longitudinal groove 19, and curved forming faces 20 at opposite sides of the groove. The upper die is fixed by screws 21 to a head 22 which is secured by screws 23 (Figure 4) to a vertically reciprocating press member 24. The forming portions 16 and 17 of the lower die have a reentrant curvature, and the forming portions 19 and 20 of the upper die have a salient curvature, the dies being adapted to form, on a sheet metal strip interposed between them, the 60 curved portion having the curved rib 25 and the lateral flanges 26 shown by Figure 12. The forming dies have flat end faces 27 which contact with portions of the strip so that flat portions 28 are left on the strip, 70 from which the prongs 29 are formed by the punching dies as hereinafter described.

The strip is fed into the machine in the direction of the arrow α (Figure 1) by feed rolls 61, which are rotated intermittently by 75 suitable automatic mechanism (not shown) and feed the strip a distance corresponding to the length of a stiffener when the dies are separated, and remain at rest while the dies are operating.

80 Fixed to the base 12 at one end of the lower forming die is a lower punch die block 30 (Figure 7) having an opening 31. An upstanding lower punch die 32 is fixed to the block between the ends of the opening 31, 85 and projects above the upper face of the block. The die 32 is hexagonal and the intersection of its side faces with its upper end face forms a cutting edge of hexagonal contour, and including two salient portions 33 and two intermediate portions 34, said portions being relatively arranged as shown by Figure 7. The opening 31 is provided with recesses 35 in its opposite sides into which the prongs 29 are bent as shown by Figure 95 7 and as hereinafter described.

Fixed to the head 22 at one end of the upper forming die is an upper punch die block 36 having a hexagonal opening 37 (Figure 7) formed to receive the lower 100 punch die 32. On the lower side of the block 36 are projections 38 constituting

punch die members adapted to enter the opening 31 of the lower die block 30 at opposite sides of the fixed upstanding die 32.

By reference to Figures 7 and 8, it will be seen that the die members 38 have reentrant cutting edges 39 formed by the intersection of the faces 40 of the hexagonal opening 37 with the bottom faces of said members. It will also be seen that the intersection of the faces 41 of the opening 37 with the bottom face of the die block 36 forms cutting edges 42 located above the reentrant cutting edges 39. The arrangement is such that when the die block 36 descends, the reentrant cutting edges 39 cooperate with the salient cutting edge portions 33 of the fixed die 32, and the cutting edges 42 cooperate with the cutting edge portions 34 of the fixed die in transversely severing a flat strip portion 28 bearing on the fixed die by detaching therefrom a hexagonal blank 44 (Figure 11). This operation severs the strip in such manner that the severed ends have the faces 45, 45 and 46 shown by Figure 9. The edges 45 are formed during the first part of the cutting action and constitute the inner edges of the prongs, which are bent downward into the recesses 33 as shown by Figure 7 by the descent of the die block 36. The edges 46 are formed just before the block 36 reaches the lower extreme of its movement. It will now be seen that during each descent of the die block 36, a flat portion of the strip is severed and pronged at the points where it is severed, resulting in bi-pronged ends of two stiffeners having flat portions between the formed portions and the prongs. The blanks 44 pass upward through the opening 37 in the die block 36, and through openings 48 and 49 (Figure 5) formed in the head 22 and press member 24.

After each feed movement of the strip, the descent of the press member 24 causes the described formation of the strip portion between the forming dies, and the severance of a previously formed portion by the punching dies, the latter acting to prong the leading end of the strip and the rear end of the severed portion, which is thus converted into the completed stiffener shown by Figure 12.

After each forming and punching operation, the strip is raised from the lower forming die, and the completed stiffener is raised from the fixed die block 30 by spring-pressed lifting pins 50 movable in guides in the lower forming die and the base 12 and bearing on the under side of the strip, and a spring-pressed lifting pin 51 movable in a guide in the die block 30 and in the base and bearing on the under side of the completed stiffener.

Edgewise displacement of the strip is prevented by edge guides formed by plates 53 fixedly connected with the base and having

slots 54, the sides of which constitute the edge guides.

The cutting edges which slit the strip to partially sever the prongs therefrom, are arranged to impart a tack-like form to the 70 prongs enabling the same to be easily driven, each prong being very narrow at its base portion and tapering therefrom to its point.

I claim:

1. Shank-stiffener forming mechanism 75 comprising a fixed base, a reciprocating head movable toward and from the base, a pair of forming dies including a lower die fixed to the base and a complemental die fixed to the head, the dies being formed to longitudinally curve and emboss a portion of an elongated stiffener strip and leave flat portions at opposite ends of the curved and embossed portions, and strip-severing and pronging mechanism arranged to act on a 80 flat portion of the strip in advance of a formed portion thereof, said mechanism including means for cutting, from the flat portion, a polygonal blank, and thereby forming an opening extending from edge to edge 85 of the flat portion, so that the latter is transversely severed, portions of the margin of said opening defining the inner edges of four prongs, means being provided for simultaneously bending said prongs from the 90 plane of the flat portion, so that bi-pronged 95 ends of two stiffeners are simultaneously formed, said stiffeners having flat portions between the formed portions and the prongs. 100

2. Shank-stiffener forming mechanism comprising a fixed base, a reciprocating head movable toward and from the base, a pair of forming dies including a lower die fixed to the base and a complemental die fixed to the head, the dies being formed to longitudinally curve and emboss a portion of an elongated stiffener strip and leave flat portions at opposite ends of the curved and embossed portions, and strip-severing and pronging mechanism arranged to act on a 105 flat portion of the strip in advance of a formed portion thereof, said mechanism including a fixed punch die block on the base at one end of the lower forming die, arranged to bear on the underside of a flat portion of the strip and provided with an opening, a fixed upstanding die extending through said opening and provided with a cutting edge of substantially hexagonal contour projecting above the die block, and a 110 reciprocating die block on the head provided with downwardly projecting die members adapted to enter the opening in the fixed die block, said reciprocating block having reentrant cutting edges cooperating with portions of the said hexagonal cutting edge, and intermediate cutting edges cooperating 115 with other portions of the hexagonal cutting edge, the said cutting edges being arranged to sever a substantially hexag- 120

125

130

onal blank from a flat portion of the strip between two formed portions thereof and thereby separate a formed end portion from the strip and simultaneously form the inner edges of two pairs of prongs, the die blocks having means for simultaneously bending said prongs from the plane of the flat portion, so that bi-

pronged ends of two stiffeners are simultaneously formed, said stiffeners having flat portions between the prongs and the formed portions.

In testimony whereof I have affixed my signature.

WILLIAM H. NICKERSON.
